WILLIAM C. STEWART, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-LOCATING DEVICE.

1,315,171.

Specification of Letters Patent.

Patented Sept. 2, 1919.

Application filed June 15, 1916. Serial No. 103,845.

To all whom it may concern:

Be it known that I, WILLIAM C. STEWART, a subject of the King of Great Britain, residing at Swampscott, in the county of Essex and State of Massachusetts, have invented certain new and useful Improvements in Sole-Locating Devices; and I do hereby declare the following to be a full, clear, and exact description of the invention, 10 such as will enable others skilled in the art to which it appertains to make and use the same.

This invention relates to sole locating devices.

15 In many machines for operating upon shoe soles, such for instance as marking machines, slashing machines, skiving machines, molding machines and rounding machines, the sole is located preparatory to being operated upon by either a toe or a heel gage, or by a combination of such gages. The different widths of the same size and style of a sole, and also the different styles of soles of the same size and width vary in 20 length. This variation in the length does not always occur at the toe end, or at the heel end, but may occur at both ends; and for this reason the use of toe or heel gages to locate soles of different sizes, widths and 25 styles in machines of the classes above referred to is troublesome on account of the many different adjustments required, and often leads to inaccurate and unsatisfactory results.

30 The primary object of the present invention is to provide an improved and simplified means for locating soles in machines of the classes above referred to, which will be free from the objectionable features incident to the use of heel or toe end gages.

35 In accordance with this object, one feature of the invention contemplates the provision, in a machine for operating on soles which has devices with relation to which a sole is to be located before being operated upon, of a sole locating device having a 40 feeler to coöperate with the edge contour of the sole to determine the longitudinal position of the sole.

45 In the illustrated embodiment of the invention, the sole locating device is employed to position a sole on the mold of a sole molding machine so that the ball line of the sole

will register with the break on the face of the mold.

55

Accordingly, another feature of the invention contemplates the provision in a sole molding machine having coöperating molds, of means for locating a sole in the proper position with relation to the molds including a feeler coöperating with the edge contour of the sole to determine the longitudinal position of the sole. In the simplest and most efficient form of the invention which has yet been devised a pair of centering 60 gages are arranged to contact with opposite sides of the sole and a feeler mounted upon one of the gages and coöperating with the edge contour of the sole serves to control a mechanism which locks the two gages 65 against transverse movement when the sole has been located in a predetermined longitudinal position.

70

The invention also includes other features of construction and a combination of parts, 75 which are hereinafter described and set forth in the claims.

The various features of the invention are illustrated in the accompanying drawings, 80 in which Figure 1 is a view in side elevation illustrating a sole molding machine embodying the preferred form of the invention; Figs. 2, 3 and 4 are detail plan views of one of the pressing molds, showing the different positions which the sole locating 85 mechanism occupies with relation to the mold; Fig. 5 is a detail view in front elevation of the mold and sole locating device shown in Fig. 2; Fig. 6 is a vertical section through the mold taken on the line 6—6 of 90 Fig. 2, showing the heel centering fork; Fig. 7 is a diagrammatic view illustrating the different lengths for the different widths of soles of the same size and style; and Fig. 8 is a diagrammatic view illustrating the 95 different lengths of soles for the different styles of soles of the same size and width.

The sole pressing machine illustrated in the drawings is substantially the same in its construction and operation of parts as the sole pressing machine shown in the patent to Preble, No. 1,004,076, patented September 26, 1911. This machine is provided with two sets of sole molds, but inasmuch as both sets of molds are constructed and operated in the same manner, one set only will 100 105

be illustrated and described. The upper mold 10 is adjustably mounted upon a cross head 12 which is supported by the machine frame. The lower mold 14 is mounted upon a slide 16 which slides in guideways formed in a vertically reciprocating carrier 18. The carrier 18 is reciprocated during the molding operation by means of a crank 20 which is connected by a link 22 with toggle arms 24, one of the toggle arms being connected to the carrier 18, and the other arm being connected to the machine frame. In the position shown in Fig. 1 the lower mold is located in the position of presentation out of alignment with the upper mold. During the initial movement of the active stroke of the crank 20 the lower mold 14 is brought into an aligned position with the upper mold 10. To accomplish this, the slide 16 is connected by a link 26 with a bell crank 28 pivoted on the carrier 18. The bell crank 28 is connected by means of a link 30 with a lever 32 which is pivoted in the machine frame, and has one arm attached to a spring 34 which is connected to the machine frame. With this construction the initial movement of the carrier will bring the slide 16 back against a stop 36 on the carrier 18, in which position the molds are in alignment. With the continued operation of the crank 20 to bring the molds into pressure relation, the toggle 24 is straightened and the movement of the slide actuating mechanism is taken up in the spring 34.

The parts so far described are the same as those illustrated and described in the patent above referred to, and reference is hereby made to said patent for a detailed description of the construction and operation of these parts.

The principal operation performed by the sole molding machine is to form a sharp bend in the sole at the juncture of the shank and forepart, or what is known as the ball line of the sole. This sharp bend in the sole mold is shown at 38 in Fig. 1, and designated by the line 38 in Figs. 2, 3 and 4. To properly mold the sole, the ball line of the sole should be made to coincide with the line 38 on the mold. In Fig. 7 is shown the outline of a series of patterns of finished soles of the same size and style, which illustrate the variation in the length of soles for different widths. Each of these soles has a different length, and the ball lines of all do not coincide. In Fig. 8 are shown diagrams of a series of patterns of finished soles of the same size and width, which illustrate the variation in length of soles for the different styles. In this view, the ball lines of the sole coincide, and the soles vary in length at each side of the ball line. It is apparent that the use of a heel or a toe gage to locate even a finished sole with respect to the ball line of a mold is apt to produce inaccurate results.

When operating, however, on block soles, such as illustrated in dot and dash lines in Figs. 2, 3 and 4, in which only the shank and forepart of the sole has been shaped, measurements with reference to the heel or 70 the toe ends would lead to even more inaccurate results. This is true, especially in the case in which block soles are employed in making soles several sizes smaller than the rough size of the block sole.

To accurately locate the ball line of a block sole on the ball line of the mold with the locating mechanism illustrated in the drawings, a pair of centering gages are employed which contact with opposite edges 75 of the sole intermediate its ends, and locate the sole by reference to its contour. The centering gages 40 and 42, Figs. 2, 3, 4 and 5, are arms projecting from hubs 44 and 46, respectively, which are pivoted on an adjustable block 48. The block 48 is mounted on the slide 16, and is adjustable transversely thereof by means of slots 50 and set screws 52, to permit the gages to be accurately positioned with reference to the different types of molds. As shown in Figs. 5 and 6, the upper face of the mold 14 is beveled from its center line toward the edges, and consequently the hubs 44 and 46 are set on an angle to permit the gages to 90 move toward and from each other substantially parallel with the face of the mold. Lugs 54 project forwardly from the hubs 44 and 46, between which is connected a strong tension spring 56, that acts to normally close the gages toward the center of the mold. The gages are geared together by means of intermeshing gear segments formed on arms 58 and 60, which project from the hubs 44 and 46, respectively. When a sole 100 is in place between the gages, one edge contacts with a roll 62 on the gage 40, Fig. 5, and the opposite edge contact with a pair of rolls 64 on a feeler 66, which is pivotally mounted in the forward end of the gage 42. 105 With this construction the spring 56 will cause the gages to follow the contour of the sole and since the gages are geared together they will center the sole.

When the lower mold 14 is in the position of presentation illustrated in Fig. 2, the centering gages are held apart a sufficient distance to permit the shank portion of a sole to be readily inserted between them. To this end an arm 68 projects back from the gage 40, and carries a roll 70, which engages a cam face 72 formed on a cam plate 74. The cam plate 74 is adjustably mounted by means of slots and bolts 76 upon the carrier 18.

To position a sole with the locating device, the shank portion of the sole is placed between the gage 40 and feeler 66, and pushed back toward the heel end of the mold. As the sole is moved back, the gage 40 and feeler 66 follow the contour of the 110 115 120 125 130

sole and are spread apart as the forepart of the sole is advanced between them. When the ball line of the sole has been brought into register with the ball line of the mold, 5 the feeler acts to lock the gages from further spreading movement, and holds the sole from further advancing movement. To accomplish this result, a link 78 is connected between the feeler 66, and a pawl 80 which 10 is pivotally mounted on the gage 42. The pawl is arranged to engage with a ratchet plate 82, which is pivotally mounted on the stud 84, upon which the gage 42 is pivoted. A gear segment 86 is formed on the ratchet 15 plate which meshes with a gear segment on an arm 88 fixed by means of dowel pins 90, and a screw 92 upon the arm 58. The pawl 80 is normally held in engagement with the ratchet 82 by a spring 94 which is connected 20 between the tail of the pawl and the gage 42.

When the feeler is in engagement with the shank portion of the sole, as shown in Fig. 2, it will be rotated by the gage spring 56 into such an angular position on the gage 42 25 that the pawl 80 will be drawn out of engagement with the ratchet 82 against the action of the spring 94. With the ratchet unlocked, the gages are free to spread apart as a sole is moved through them. As the sole 30 is moved through the gages the feeler will follow the sole edge contour and will be rotated sufficiently by the change of curvature of the sole, when the ball line of the sole registers with the ball line of the mold, to permit the pawl 80 to engage the ratchet 82. The engagement of the pawl with the ratchet locks the gages from further spreading movement and holds the sole from advancing further through the gages. The angular 35 position of the feeler 66 on the gage 42, when the gages are locked, is shown in Fig. 3. This position is determined when the contour of the sole edge changes from divergent to the center line of the mold, to 40 convergent to the center line of the mold, or approximately the widest portion of the sole. The movement of the ratchet plate 82 by the arm 88 is very rapid since they are geared to a high ratio, and the ratchet teeth 45 can be comparatively large to positively lock the gages from spreading movement when the feeler has reached the proper angular position upon the gage 42. By the above construction, the sole is positioned entirely 50 by reference to the contour of the sole edge. Since the gages follow the contour of the sole and locate the sole by reference to its edge curvature they do not need separate adjustments to provide for the different sizes 55 and widths of soles. It will be seen that the feeler, in addition to determining the longitudinal position of the sole on the mold, also cooperates with the gage 42 in centering the sole upon the mold.

65 The operation of the sole locating feeler

depends upon its angular position upon the gage, so that the heel end of the sole should be centered to insure that the ball line of the sole will be brought into register with the ball line of the mold when the feeler operates to lock the gages, and to insure that all of the soles will be uniformly positioned. The heel end of the sole is centered by a pair of spring clips 96 which form a fork to receive the heel end of the sole, see Figs. 2, 3, 4 70 and 6. The clips are secured to the blocks 98, which are slidably mounted upon a rod 100, supported on a carrier 102. An adjusting screw 104, having a right and left thread, is fixed in the carrier 102 and threaded into the blocks 98 so that the movement of the screw 104 will give the clips 96 a relative receding and approaching movement. The carrier 102 is slidably mounted upon a rod 106 which is secured between the mold 14 75 80 and a bracket 108 secured to the slide 16, and the carrier may be adjusted in different positions on the rod 106 for treating different lengths of soles.

As will be observed in Fig. 8, the ball line 90 of a sole occupies different angular relations relatively to the center line of the sole for the different styles. For this reason the heel clips may be adjusted to properly center the heel end of the sole and the link 78 connecting the gage feeler 66 and pawl 80 is made adjustable by means of a slot 110 and screw 112 to permit the feeler 66 to be set to occupy different angular positions for locking the ratchet by the pawl 80. By 100 this adjustment and the adjustment of the gage block 48 transversely of the slide 16, the angular relation of the ball line of the various styles of soles can be made to register with the ball line 38 of the mold 14. 105

As shown in Figs. 2 and 3, the gages move back and forth across the face of the mold and must be withdrawn from the sole to allow the sole to be molded. This result is accomplished when the mold 14 is moved from the position of clearance into alignment with the upper mold 10. During this movement the sole is automatically clamped in position upon the mold 14, and the side gages withdrawn from the face of the mold 14, so that the upper mold 10 can be brought 110 down into contact with the sole. The sole is clamped in position by a clamping arm 114 which is fixed on a shaft 116 pivoted in the bracket 108. A cam lever 118, Figs. 1, 2, 3 and 6, is fixed on the shaft 116, and carries a roll 120 which works in a cam groove 122 formed in a plate 124 secured to the carrier 18. The movement of the roll 120 in the cam groove 122 operates to 115 bring the clamping arm down to clamp the sole between a face 126 on the arm 114, and a plunger 128 mounted in the mold 14. 120

Before the side gages can be spread away 125 clear of the mold 14, the pawl 80 must be 130

released from the ratchet 82 to permit the gages to be spread apart. To this end a cam plate 130 is loosely mounted upon the stud 84, and is provided with a cam groove 132 which engages a roll 134 on a plate 136 adjustably mounted upon the carrier 18 by means of slots and bolts 138. When the mold 14 is in the position of presentation, the cam plate is in the position shown in Figs. 10 2 and 3, and as the mold is moved into alignment with the upper mold, a face 140 on the plate 130 engages a roll 142 on the pawl 80, and lifts the pawl clear of the teeth of the ratchet 82, as shown in Fig. 4. The link 78 has a slot 144 which permits a movement of the link relatively to the feeler 66 while the pawl is being unlocked from the ratchet. When the cam plate 130 has been operated to unlock the pawl from the ratchet, 15 the roll 70 on the arm 68 is timed to engage with a cam face 146 on the cam plate 74, and spreads the side gages to the position shown in Fig. 4. The gages remain in this position while the sole is being pressed, and when the mold is moved into the position of clearance, the cam plate is moved back into the position shown in Fig. 2, to arrange the gages so that they will be ready to position another sole.

30 The preferred form of the invention having been thus described, what is claimed as new is:

1. A machine for operating on shoe soles having, in combination, devices with relation to which a sole is located before being operated upon including a gage, a feeler movably mounted on the gage, means to hold the feeler in engagement with the edge of the sole as the sole is moved into position, 35 and means controlled by a movement of the feeler on the gage as the feeler follows the contour of the sole to determine the longitudinal position of the sole.

2. A sole molding machine, having, in combination, sole pressing molds, sole centering members movable toward and from each other between the molds and arranged to act on opposite sides of a sole intermediate its ends, locking mechanism for locking said 50 members against movement away from each other, a feeler coöperating with the edge contour of the sole to control said locking mechanism, and means for unlocking and separating said members prior to the pressing action of the molds on the sole.

3. A sole molding machine, having, in combination, upper and lower sole pressing molds, means for actuating the molds to produce pressure and clearance and for moving 60 the lower mold to a position of presentation out of alignment with the upper mold, sole centering members arranged to move toward and from each other over the lower mold and act on opposite sides of the sole intermediate 65 its ends, and means for separating said

members as the lower mold moves to a position of clearance in alignment with the upper mold.

4. A sole locating device for machines for operating on shoe soles, having, in combination, gages mounted on opposite sides of the operative position of the sole, and a feeler movably mounted on one of said gages and arranged to coöperate with the edge contour of the sole to determine the longitudinal 70 position of the sole.

5. A sole locating device for operating on shoe soles having, in combination, devices for operating upon a sole, means, including a sole edge feeler for determining the transverse position of the sole with relation to said devices, and means connected with the feeler to determine the longitudinal position 80 of the sole with relation to said devices.

6. A sole locating device for machines for 85 operating on shoe soles having, in combination, sole centering gages movable toward and from each other, a feeler on one of the gages to follow the contour of a sole edge, locking mechanism to lock said gages against 90 movement away from each other, and connections between the feeler and the locking mechanism.

7. A sole locating device for machines for 95 operating on shoe soles having, in combination, mechanism for centering one end of a sole, sole centering gages mounted on opposite sides of the sole to center the other end of the sole, sole contacting devices including a feeler mounted on said gages, means 100 to move said gages toward one another, and means connected with the feeler and movable independently of the gages to determine the longitudinal position of the sole.

8. A sole locating device for machines 105 for operating on shoe soles, comprising gages movably mounted to extend on opposite sides of a sole and a feeler movably mounted on one of said gages, and means connected with the feeler to determine the longitudinal 110 position of the sole.

9. A sole locating device for machines for operating on shoe soles having, in combination, a pair of side gages geared together for movement in unison, a feeler pivoted to 115 one of the gages and arranged to make a multipoint contact with the edge of a sole, and means connected with said feeler to determine the longitudinal position of the sole.

10. A sole locating device for machines for operating on shoe soles having, in combination, a pair of side gages geared together for movement in unison, devices on one of said gages arranged to make a multipoint contact with the sole edge, one of said contacts being movable relatively to the gages as the contacts follow the sole edge contour, means to move the gages toward the center of the sole, and means connected 125 130

to said movable contact to determine the longitudinal position of the sole.

11. A machine for operating on shoe soles, having, in combination, devices with relation to which a sole is located before being operated upon, and means for locating a sole in proper position with relation to said devices including a feeler past which the sole is moved in being located coöperating 10 with the edge contour of the sole to stop further movement when the sole has reached its proper position.

12. A machine for operating on shoe soles having, in combination, devices with relation to which a sole is located before being operated upon, and means for locating a sole 15 in proper position with relation to said devices including feelers for contacting with

the opposite edges of the sole and arranged to bear against and follow the edge contour of the sole as the sole is moved past the feelers to determine the longitudinal position of the sole.

13. A sole pressing machine having, in combination, sole pressing members, sole centering members connected for movement toward and from one another, feelers mounted on said centering members, means to clamp a sole in position on one of said pressing members, mechanism to move the pressing members relatively into and out of pressure relation, and means to withdraw the feelers from the sole after the sole has been clamped in position.

WILLIAM C. STEWART.
